(57) **CLAIM**

I claim the ornamental design for the blower housing, as shown and described.

DESCRIPTION

FIG. 1 is a top perspective view of the blower hosing, showing my new design.

FIG. 2 is a bottom perspective view of the blower hosing, showing my new design.

FIG. 3 is a side planar view of the blower hosing, showing my new design.

FIG. 4 is another side planar view of the blower hosing, showing my new design.

FIG. 5 is another side planar view of the blower hosing, showing my new design.

FIG. 6 is another side planar view of the blower hosing, showing my new design.

FIG. 7 is a top planar view of the blower hosing, showing my new design; and,

FIG. 8 is a bottom planar view of the blower hosing, showing my new design.

The broken lines represent environment that forms no part of the claim.
